UNITED STATES PATENT OFFICE.

HAROLD V. PEARCE, OF DENVER, COLORADO.

APPARATUS FOR SETTLING SLAG.

SPECIFICATION forming part of Letters Patent No. 795,163, dated July 18, 1905.

Application filed June 10, 1903. Serial No. 160,899.

To all whom it may concern:

Be it known that I, HAROLD V. PEARCE, a subject of the King of Great Britain, residing at Denver, in the county of Arapahoe and State of Colorado, have invented a certain new and useful Improvement in Apparatus for Settling Slag, of which the following is a full, clear, and exact description.

The object of this invention is to provide for the separation or recovery of metallic copper or matte from the slag of smelting-furnaces in an operation that is practically continuous of the smelting operation and while the slag is still fluid.

15 The slag while hot and still fluid is run into a vessel which may be by reason of its function and operation called a "settler" and in which the particles of matte or metal carried in the slag are permitted to separate by gravity from the slag and accumulate in a pocket specially provided therefor and from which such separated matter may be separately removed or recovered, the slag being discharged independently. This operation may be accomplished without the aid of an oxidizing flame or blast or other extraneous heat and simply by permitting gravitation to act while the slag is in a fluid condition. An apparatus suitable for this purpose consists of a cylinder having a refractory lining and an adit and a separate exit for the fluid slag and an independent collecting and discharging pocket wherein the metal is deposited and from which it is recoverable. The vessel is mounted so as to be capable of being oscillated in the performance of its functions, and it is designed to be used without the employment of any heat other than the heat of the fluid slag, although it might be advisable to heat up the vessel before the initial charge of slag, in order to prevent sudden cooling or chilling of the slag.

In the accompanying drawings, illustrating the invention, in the several figures of which like parts are similarly designated, Figure 1 is a side elevation of the apparatus including one form of mechanism for oscillating it. Fig. 2 is a top plan view including another form of oscillating mechanism. Fig. 3 is a rear elevation including a third form of oscillating

mechanism. Fig. 4 is a longitudinal section illustrating various positions given to the vessel in the practice of the invention.

The vessel 1 preferably is constructed of a cylindrical shell 2, of metal, and has a bottom 3 secured thereto by clamping-bands 4, united by bolts 5 or otherwise in a removable manner, so that the bottom may be detached at pleasure in order to gain access to the interior of the vessel for repairs and other purposes. This bottom is provided with a spout 6 adjacent to an exit or tap-hole 7. The opposite end or nose 8 of the vessel is formed of convergent lower and side walls and a top wall, meeting in an adit 9. The vessel is lined with fire-brick or other refractory material or substance, and particularly such substance as is capable of retaining heat. The vessel is supplied with trunnions 10, which are mounted in bearings 11 on standards 12. The trunnions 10 may be applied to or may be integral with an encircling band 13 made in halves bolted or otherwise united. This band is preferably of somewhat larger diameter on the inside than the diameter of the shell, so as to be free of the rivets in the shell, and is mounted upon this shell through the interposition of spacing-blocks and is secured to the shell by means of lugs 14, to which it is bolted, the lugs in turn being riveted to the shell. The lugs 14 are secured to the shell some distance from the band so as to leave a considerable space between the lugs and the sides of the band in order that the band may be adjusted, and with it the trunnions, thereby to shift the center of motion as near as desired to the center of gravity. As shown, the spaces between the lugs and the band may be taken up by filler-blocks 15.

One side of the vessel is provided with an outwardly-projecting or offset conical pocket or chamber 16, having an exit or tap-hole 17. A flanged collar 18 may be arranged about the pocket in order to reinforce its connection with the shell of the vessel. This pocket is the collecting device herein referred to.

Any suitable means may be used for oscillating or tilting the vessel, and in Fig. 1 I have shown a worm 19 engaging a worm-wheel 20, the worm being actuated by a hand-

wheel 21. In Fig. 2 the worm 19 is driven by a crank-shaft 22 with interposed beveled-gear connections of usual construction. (Not shown.) In Fig. 3 the worm 19 is connected by beveled gears 23 with a power-shaft 24, or any other mechanism operated by hand or power may be used for tilting or oscillating the vessel upon its trunnions.

The slag to be "settled" in accordance with 10 this invention is skimmed into the vessel 1 through the adit 9 and allowed to stand for a while and so long as it remains fluid, with the result that the metal or matte separates from the slag by gravity and accumulates eventually in the pocket 16.

When the furnace is being skimmed of slag, the position of the settler or vessel 1 is as shown in dotted lines A, Fig. 4, or at about 20 an inclination of, say, twenty degrees, so that the nose or adit end is low enough to receive the flowing slag by a spout. If, however, the settler is placed low enough, of course a horizontal position, as shown in full lines, is sufficient. As the slag flows into the settler much 25 of the matte will settle in the chamber 16. When the skimming is finished, the settler is turned to the position shown in Fig. 1 and also shown in Fig. 4 by dotted lines B or at about 30 an upward inclination of, say, twenty-four degrees. The matte still in the slag will settle in the lower end of the vessel 1. When sufficient time has elapsed for such settling, the vessel is again turned to the position A, Fig. 4, with the nose down, and the previously-settled matte in the vessel then flows 35 under the slag into the pocket 16, joining that already caught there. The vessel is again turned into the position of Fig. 1 with the nose up and the slag tapped off through the 40 tap-hole 7 into any convenient vessel by which it may be removed, after which the matte accumulated in the pocket 16 is tapped into a pot on wheels or any other suitable receptacle,

and any overlaying slag is run into another receptacle, and the vessel is then ready to receive another charge. 45

The drawings do not fully show the details of construction; but they do indicate them sufficiently to illustrate the principle of the invention and to enable any one skilled in the 50 art to carry out the invention.

I am aware that prior to my invention in the metallurgy of copper and iron a vessel substantially like a Bessemer converter has been constructed with a mixing-pocket or a 55 catch-basin for the metal which is to be therein treated in connection with an oxidizing blast; but so far as I am aware it has not hitherto been attempted to recover by gravity from the slag of a smelting-furnace the 60 metal or matte carried by it by means of a vessel having a collecting-pocket into which the settled or separated metal is introduced by oscillation of the vessel and while the slag is fluid and without extraneous heat. 65

What I claim is—

A heat-retaining vessel mounted on trunnions and having at one end a bottom provided with a tap-hole, and having at its other end a nose formed with convergent side and 70 lower walls and a top wall provided with an adit, a conical pocket arranged below the nose and having a tap-hole, and means to oscillate the vessel, whereby fluid slag may be treated 75 by gravitation and the metal or matte therein separated and collected in the pocket and thence withdrawn through the tap-hole therein and the slag withdrawn through the tap-hole in the bottom of the vessel.

In testimony whereof I have hereunto set 80 my hand this 5th day of June, A. D. 1903.

HAROLD V. PEARCE.
